UNITED STATES PATENT OFFICE.

CHARLES H. MAGGS, OF ROCHESTER, NEW YORK.

FOLDING TABLE.

1,165,991.

Specification of Letters Patent. Patented Dec. 28, 1915.

Application filed August 24, 1914. Serial No. 858,172.

To all whom it may concern:

Be it known that I, CHARLES H. MAGGS, of Rochester, in the county of Monroe and State of New York, have invented certain new and useful Improvements in Folding Tables; and I do hereby declare the following to be a full, clear, and exact description of the same, reference being had to the accompanying drawings, forming a part of this specification, and to the reference-numerals marked thereon.

My invention has for its object the provision of a foldable table such as may be employed by hotels and caterers for banquet and other purposes, and it contemplates a novel and improved construction which can be manufactured at a reasonable cost.

A further purpose of the invention is to provide a construction that possesses the necessary qualifications of strength and endurance, and which at the same time can be readily folded or unfolded, and insures holding the parts rigidly in either relation.

To these and other ends the invention consists in certain improvements and combinations of parts, all as will be hereinafter more fully described, the novel features being pointed out in the claims at the end of the specification.

In the drawings: Figure 1 is a bottom plan view of a table equipped with my improvements, and showing the legs unfolded; Fig. 2 is a side elevation of a portion of the table; Fig. 3 is an enlarged perspective view of the keeper, and Fig. 4 is a sectional view on the line 4^a—4^a, showing the leg support folded.

Similar reference characters in the several figures indicate the same parts.

In a more specific aspect, the invention consists of a leg support which has a hinged relation to the table top and is adapted to be folded and retained in such folded position rigidly, similar retaining means acting to hold the leg support in its unfolded or open position with sufficient force to obviate accidental displacement, or collapsing of the table.

In the present embodiment the leg support includes a portion A connecting the legs B, which are attached to the table top C by means of hinges D. The leg support, when in its unfolded position, as shown in Fig. 1, rests against a stationary strip or brace E, which engages the legs B, thus pre-

venting any undue strain on the locking and retaining means which I will now describe.

Secured to the under face of the table top is a keeper, while F designates a locking member, which is connected at one end to the leg support while its opposite end is movable longitudinally of the keeper and may be held in locking relation at either end thereof by suitable retaining means. The locking member F is preferably in the form of an elongated link, and is pivoted to a leaf G which is attached to the leg support A.

The keeper preferably comprises a plate H which is secured to the under face of the table top by means of offset ends I, and is arranged in spaced relation to the table top, thereby affording a slot or way J within which the locking member travels. At its opposite ends, the plate H is provided with recessed or retaining portions K afforded by recesses or grooves adapted to receive the free end of the locking member F.

Retaining means are also provided for holding the locking member at either end of the keeper, in folded or unfolded position, and in the embodiment shown, in engagement with one or the other of the recessed portions K, and this I preferably accomplish by employing a supplemental plate L which is arranged above the part of the keeper already described, the plates H and L preferably being attached to the table by securing devices common to both. The plate L has struck therefrom a pair of leaf springs M which are formed with downwardly bent end portions extending through openings N in the keeper, and normally resting in engagement with the recessed portions K. Each of the springs M acts with sufficient force to hold the leg support rigidly in either folded or unfolded position, as shown in Figs. 2 and 4 respectively. The springs coöperate with and engage the free ends of the locking member, and when it is desired to release the latter, this can be done by depressing the end of the controlling spring, permitting the locking member to be moved out of engagement with the recessed portion

and longitudinally of the keeper to the opposite end thereof, where it is automatically moved into engagement with the other recessed portion and retained there by the corresponding spring.

As a rule, two of the structures such as I have described will be employed for each

table, one for each leg support, and the device affords an extremely efficient arrangement which is of simple construction and fully answers the purposes for which it is 5 designed, having in mind the ready foldability of the table legs and a rigid support for them when in operative position.

The structure is not limited as to scope 10 to the specific arrangement described, as the invention may be otherwise carried out without departing from the terms of the appended claims.

I claim as my invention:

1. A retaining device comprising opposite plates in spaced relation to each other, one of the plates having transversely extending grooves at its ends, the other plate having springs formed integral therewith and extending longitudinally from a point intermediate the ends of the device, and overlying the grooves intermediate the ends thereof.

2. A retaining device comprising a pair of comparatively wide plates arranged in spaced relation to each other, one of the plates having oppositely arranged grooves extending from one edge to the other, and comparatively wide flat springs secured to the other of said plates to overlie the grooves 30 before mentioned and extending longitudi-

nally from a point intermediate the ends of the device.

3. The combination with a table top, of a leg support hinged to the top, a keeper secured to the lower face of the table top comprising a top plate and a bottom plate disposed in spaced relation to the table top and provided with a recessed or retaining portion at each end, a locking member consisting of an elongated link, one end of which is connected to the leg support and the opposite end of which is movable longitudinally of said keeper, and oppositely disposed leaf springs formed from said top plate of the keeper and bearing against said recessed portions whereby to hold the locking member in engagement with either of the recessed portions.

4. A retaining device comprising opposite plates in spaced relation to each other, one of which is provided with transverse grooves at its ends, while the other carries springs extending longitudinally from points between the ends of the device and overlying the aforementioned grooves.

CHARLES H. MAGGS.
